SHERMAN T. ALLEN, OF LOS ANGELES, CALIFORNIA.

RECIPROCATING SLEEVE-VALVE.

1,257,777.

Specification of Letters Patent. Patented Feb. 26, 1918.

Application filed November 16, 1916. Serial No. 131,762.

To all whom it may concern:

Be it known that I, SHERMAN T. ALLEN, a citizen of the United States, residing at Los Angeles, in the county of Los Angeles and State of California, have invented new and useful Improvements in Reciprocating Sleeve-Valves, of which the following is a specification.

This invention relates to a reciprocating sleeve valve for internal combustion engines and particularly pertains to a valve of the slideable telescoping sleeve type.

It is desirable in valves of the above type that the inner and outer telescoping valve members resiliently grip each other so as to form a close sliding joint therebetween and also that the outer valve sleeve yieldably contact an encircling cylinder wall with both sleeves adapted to expand and contract with varying temperatures without binding. To effect the foregoing stated results it has been found desirable to split the sleeves longitudinally and to so form the inner sleeve that when it is placed within the outer sleeve it will exert an outward pressure thereon to expand it against the cylinder wall. It has been found that such split sleeves are difficult to pack to prevent the escape of gases along the slit and also that there is a tendency of the sleeves to bind on strains being imposed thereon, as in reciprocating same, by reason of the sleeves being capable of slight distortion or twisting due to the presence of the slit. It is the object of this invention to so form the split in the sleeves as to obviate twisting thereof and which construction will facilitate mounting of the sleeves so that they may be effectively packed.

Another object is to provide a mounting for the sleeves, such as to permit of their being properly lubricated without danger of the lubricating oil escaping in excessive quantity into the engine cylinders.

A further object is to provide a simple means for actuating the sleeve valves from their upper ends and from a point above the engine cylinders.

Other objects will appear hereinafter.

The invention is illustrated, by way of example, in the accompanying drawings in which:

Figure 1 is a view, in elevation showing the sleeve valves as assembled and as removed from the engine cylinder.

Fig. 2 is a view in vertical section as seen on the line 2—2 of Fig. 6.

Fig. 3 is a view in rear elevation opposite that shown in Fig. 1 and as seen in the direction indicated by the arrow —3— in Fig. 6. 60

Fig. 4 is a view in section and elevation illustrating the valves as applied to an engine casing and illustrating the valve as seen in the direction indicated by the arrow —4— in Fig. 1. 65

Fig. 5 is a detail in perspective of the telescoping sleeve valves, with parts broken away, showing the construction and arrangement of the splits therein.

Fig. 6 is a detail horizontal section as seen on the line 6—6 of Fig. 1.

More specifically, 7 indicates an engine casing of any suitable construction formed with the usual engine cylinder 8 to receive the engine piston. In carrying out the present invention the casing 7 is formed with a vertical cylinder 9 above the piston cylinder 8 open at both ends and communicating at its lower end with the piston cylinder. The upper edge of the cylinder 9 is formed with a channel 10 to provide a seat for a flange 11 formed on a removable cylinder head 12, which head projects downwardly into the cylinder 9 and has its outer wall spaced from the inner wall of the latter. A cap plate 13 covers and is secured to the engine casing and extends over the cylinder head 12; the cylinder head being secured to the cap plate 13 by means of a threaded stem 14 formed on the cylinder head, which projects through the cap plate to receive a nut 15 which, when screwed on the stem 14, serves to tightly clamp the cylinder head against the under side of the cap plate. The cap plate is formed with a water space which opens to the interior of the cylinder head so as to water-cool the latter. The cap plate 13 is formed with an opening 16 which communicates with a chamber 17 leading to the cylinder 9 through the side wall thereof, the opening 16 and chamber 17 being provided to receive a pair of pitman rods 18 and 19 which connect with separate wrist-pins or cranks on a suitable drive shaft carried on the cap plate and which pitman rods extend downward into the chamber 17 and are pivotally connected to inner and outer sleeve valves 20 and 21 mounted in the space between the cylinder 9 and the cylinder head 12. The sleeve valves 20 and 21 are each 110

divided lengthwise by zig-zag slits 22 and 23, as particularly shown in Fig. 5. The slits 22 and 23, have off-set portions extending lengthwise of the sleeves which are connected by circumferential slits 24 forming parallel circumferentially extending shoulders adapted to coöperate with each other to prevent longitudinal distortion of the sleeves on lengthwise pressures being imposed thereon. This is important inasmuch as it has been found that in reciprocating split sleeves there is a tendency for the portions of the sleeves on opposite sides of the slits to move in opposite directions, thus warping the sleeves and causing them to bind. In order to prevent movement of the portions of the sleeves on opposite sides of the slits in either direction, a tongue 25 is formed on one edge portion to extend into a corresponding off-set in the adjacent portion. The shoulders and tongue, while holding the sleeves against longitudinal distortion, permit of their expanding and contracting circumferentially. This zig-zag construction of the splits also serves to prevent the leakage of gas therethrough and facilitates packing the sleeve valve as will be later described.

The sleeve valves are formed with suitable intake and exhaust ports 26 and 27 which are adapted to register, on reciprocating the sleeves in relation to each other, as is common in sleeve valve construction. The cylinder head 12 extends downward to a point adjacent the lower ends of the sleeve valves when in their lowermost position and its lower portion is formed with ports 28 and 29 adapted to register with the ports 26 and 27; the ports 28 and 29 being formed below a partition wall 30 formed in the cylinder head. The lower end of the cylinder head is threaded internally to receive a collar 31 having an annular flange 32, which flange is adapted to seat on the marginal edge of the lower end of the cylinder 9 so as to effectively close the lower end of the space between the cylinder 9 and the depending portion of the cylinder head 12 and prevent the excessive passage of oil, employed in lubricating the sleeve valves, to the piston cylinder.

In assembling the valve, the sleeve valve 20 is placed within the sleeve valve 21, with the splits offset in relation to each other, the inner sleeve valve expanding within the outer sleeve valve to effect a close sliding fit therebetween. The sleeve valves are then positioned on the cylinder head 12 and then disposed within the cylinder 9, or may be placed within the cylinder 9, after which the cylinder head will be disposed therein. The cylinder head is provided with packing rings 33 and 34 arranged on opposite sides of the ports 28 and 29, which rings bear against the inner wall of the inner sleeve valve and serve to pack the space between

this sleeve valve and the cylinder head. These packing rings are positioned so as to extend over the circumferential portions of the slits and are of such width that when the inner sleeve valve is reciprocated, the circumferential portion of the slit will not move off the packing ring. This effectively prevents the escape of gases between the inner sleeve valve and the cylinder head. After the sleeve valves are positioned in the cylinder 9 around the cylinder head, the collar 31 is set in place and the cap plate 13 mounted on the engine casing. Connections between the sleeve valves and their respective operating mechanism may then be effected.

The cylinder 9 is formed with suitable intake and exhaust ports not necessary to be here shown, but which are positioned opposite the ports in the cylinder head.

I claim:

1. In a reciprocating sleeve valve for explosive engines, the combination with an engine cylinder within which a piston is adapted to reciprocate, of a valve head formed above said cylinder and through which a valve cage is formed, a tubular reciprocating valve sleeve slidably positioned within said cage and adapted to bear against the cylindrical wall thereof, a second tubular valve sleeve slidably mounted within said first sleeve, ports formed through the walls of said sleeves and upon opposite sides, said ports arranged to alternately register, a cylinder head adapted to close the upper end of the valve cage and formed with a cylindrical extension projecting into the valve sleeves and adapted to provide a guide therefor, and a cylinder head collar detachably mounted in the lower end of said head and adapted to hold the valve members within the cage and to seal the valve sleeve passage-way thereof.

2. In a reciprocating sleeve valve for engines, comprising a valve cage having a cylindrical bore therethrough, a tubular core positioned within said bore and adapted to form an annular valve channel, said core having an upper flange adapted to seal the bore of the cage at its upper end, a removable flanged collar adapted to be attached to the core and seal the bore at its lower end, a pair of telescoping valve sleeves disposed around said core and within the annular valve channel, ports formed through opposite sides of the core, ports formed through opposite sides of the valve sleeves, and an actuating mechanism whereby the ports through the opposite sides of the sleeves will alternately register with ports through opposite sides of the core.

3. In a reciprocating sleeve valve for engines, comprising a valve cage having a cylindrical bore therethrough, a tubular core positioned within said bore and adapted to

form an annular valve channel, said core having an upper flange adapted to seal the bore of the cage at its upper end, a removable flanged collar adapted to be attached to the core and seal the bore at its lower end, a pair of telescoping valve sleeves disposed around said core and within the annular valve channel, ports formed through opposite sides of the core, ports formed through opposite sides of the valve sleeves, an actuating mechanism whereby the ports through

the opposite sides of the sleeves will alternately register with ports through opposite sides of the core, and piston rings positioned within channels formed around the core and 15 upon opposite sides of the ports therethrough, said rings being adapted to expand against the inner valve sleeve.

In testimony whereof I have signed my name to this specification.

SHERMAN T. ALLEN.
